UNITED STATES PATENT OFFICE.

HOWARD P. DORFF, OF CHICAGO, ILLINOIS, ASSIGNOR TO CONRAD J. DORFF, OF CHICAGO, ILLINOIS.

DISPENSING FAUCET.

Application filed April 20, 1925. Serial No. 24,381.

This invention relates to that type of liquid dispensing faucets in which at each manipulation of the appliance, a measured quantity of the liquid is forcibly ejected, and the present improvement has for its objects:

To provide a simple and durable formation and association of parts, in which the movable member of the dispensing faucet, is adapted, in a manual operation of the same, to create a pressure which as said member reaches the end of its manual actuation is adapted to forcibly eject from the chamber of the faucet a measured volume of the liquid to be dispensed. The return movement of the movable faucet member to a normal position being effected by a spring.

To provide in connection with the type of valve above described, an auxiliary stop valve operatively associated with the movable faucet member and adapted in a normal position of the faucet parts to close the outlet passage of the faucet to prevent seepage and dripping of the liquid, all as will hereinafter more fully appear.

In the accompanying drawing:—

Fig. 1, is a longitudinal sectional elevation of a faucet embodying the preferred form of the invention, with the parts shown in the normal position receiving liquid from a supply tank or container.

Fig. 2, is a companion view showing the parts in a position for a forcible discharge of liquid from the faucet.

Fig. 3, is a detail longitudinal section of a modification.

Like reference numerals indicate like parts in the different views.

In the present dispensing faucet structure, the barrel 1 is of a cylindrical form with its bore or piston chamber closed at its forward end by a centrally orificed head 2 in which the handled stem 3 of the herein-after described piston or plunger has movement and guidance. At its rear and open end the barrel 1 is fixedly attached by screw thread formations to a carrying head 4, that in turn is formed for fixed attachment to a liquid soap supply tank or the like.

The piston or plunger 5 above referred to, is of a cylindrical form having a close sliding fit along its entire length in the bore of the barrel 1 and preferably carrying a ring packing 6 to resist leakage past the piston. In the preferred construction shown, the rear portion 7 of the piston 6

is of the tubular shell form shown, in order to provide a maximum amount of space within the faucet and also permit of the use of an operating spring of a maximum length without an undue increase in the length of the faucet body.

The spring 8, above referred to, is preferably of the coiled wire type shown, and is arranged between the closed forward end of the shell 7 and the front end of the carrying head 4, aforesaid, with a tendency to force the piston 6 and piston shell 7 to the normal forward position shown in Fig. 1.

A longitudinal inlet passage 9' is formed in the carrying head 4 and has communication by an intermediate annular groove 10' with a longitudinal passage 9 in the barrel body, with the passage 9 extending a distance forward of the rear end of said barrel body to have communication with the bore 75 or chamber of said body by a lateral passage 10 preferably in the form of an annular groove in said bore as shown. The described location of the lateral passage or groove 10 a distance forward of the rear 80 end of the bore of the barrel 1, constitutes a material feature in the present construction, in that the piston shell 7 as it moves backward closes said passage 10 and converts the interior of the faucet body into a chamber of a closed nature, in which as said piston shell 7 has continued rearward movement acts to compress the gaseous upper portion of the contents of said chamber to effect a subsequent forcible discharge of the 90 liquid portion of said contents as the said piston shell 7 reaches the end of its rearward stroke as hereinafter set forth.

Near its midlength the barrel 1 is formed with a lateral outlet passage 11, preferably of the offset form shown and provided with a valve seat for an auxiliary valve member herein-after described, and the piston shell 7 is formed with a lateral passage 12 in operative relation to said outlet passage 11, 100 and so positioned that with said piston shell 7 in a forward position shown in Fig. 1, the passage 11 is closed, while with said piston shell 7 in a rearward position shown in Fig. 2, the aforesaid passage 11, will have communication with the passage 12 and the chamber of the faucet to permit a forcible ejection of the lower fluid contents of said chamber under the energy of the upper gaseous contents, compressed in the manual 110.

2
rearward movement of the piston 5 and piston shell as heretofore set forth.

With a view to maintain registry of the passages 11 and 12, when an accidental turning movement of the piston 5 and piston shell 7 takes place in actual use, the piston shell 7 is formed with a peripheral groove 13, in communication with the passage 12, and adapted for operative registry with the passage 11 aforesaid and as illustrated in Figs. 1 and 2. A like groove 14 may be formed in the bore of the barrel 1 and communicating with the passage 11 for a like object, as illustrated in Fig. 3.

15 The auxiliary valve member heretofore referred to, comprises a valve stem 15, sliding in a longitudinal passage in the barrel body 1 with its forward and preferably conical end adapted to seat itself on the valve seat 20 of the heretofore described outlet passage 11 to attain an effective closure of said passage when in place. At its rear end the valve stem 15 is provided with a lateral head 16 projecting into the path of the rear end 25 of the piston shell 7, so as to receive movement therefrom and by a removal of its conical end from the aforesaid valve seat of the passage 11 effect an opening of said passage, as the piston 5 and piston shell 7 30 nears the end of their rearward stroke. In the construction shown, the valve stem 15 is impelled to its forward and normal position by a spring 17 as shown in Figs. 1 and 2.

Having thus fully described my invention, what I claim and desire to secure by Letters Patent, is:—

35 1. In a dispensing faucet of the type described, the combination of a barrel having a cylindrical bore and a longitudinal inlet 40 passage communicating with said bore a distance in front of the rear end of the same, a carrying head attached to the rear end of the barrel and provided with a longitudinal passage and intermediate annular groove 45 adapted for communication with the longitudinal passage of the barrel, said barrel having an outlet passage a distance in front of said inlet passage, a piston arranged in said bore and having an operating stem extending outside the barrel, the piston having

a passage adapted to register with the aforesaid outlet passage with the piston in its rearward position, and a spring tending to move said piston in a forward direction.

2. In a dispensing faucet of the type described, the combination of a barrel having a cylindrical bore and an inlet passage communicating with said bore a distance in front of the rear end of the same, said barrel having an outlet passage a distance in front of said inlet passage, a piston of a straight cylindrical form having a close sliding fit along its length in the bore of the barrel and having a tubular shell portion on its rear end, an operating stem on said piston extending outside said barrel, the shell portion of the piston having a lateral passage and associated peripheral groove adapted to register with the aforesaid outlet passage with the interior of the piston in a rearward position, the outlet passage having a valve seat, a valve member moving in unison with the piston and adapted to engage said seat, and a spring tending to move said piston in a forward direction.

3. In a dispensing faucet of the type described, the combination of a barrel having a cylindrical bore and a longitudinal inlet passage communicating with said bore a distance in front of the rear end of the same, said barrel having an outlet passage of an offset form provided with a valve seat, said passage being located a distance in front of the aforesaid inlet passage, a piston arranged in the bore of the barrel and having an operating stem extending outside the barrel, the piston having a passage adapted to register with the aforesaid outlet passage with the piston in its rearward position, a spring tending to move said piston in a forward direction, a valve stem having a valve head at its forward end adapted to engage the valve seat of the outlet passage aforesaid, and at its rear end a lateral projection extending into the path of the piston, and a spring tending to move said stem in a forward direction.

Signed at Chicago, Illinois, this 15th day of April, 1925.

HOWARD P. DORFF.
